[57] CLAIM

The ornamental design for a van top, as shown and described.

DESCRIPTION

FIG. 1 is a perspective view of a van top as seen from the upper, front and right side showing my design, the partial view of a van being shown in broken lines for illustrative purposes and not forming a part of my design;

FIG. 2 is a top plan view of my design;

FIG. 3 is left side elevational view of my design, the opposite side being a mirror image thereof;

FIG. 4 is a front elevational view of my design; and

FIG. 5 is a rear elevational view of my design.
